UNITED STATES PATENT OFFICE.

LOUIS PHILIP PEREW, OF NORTH TONAWANDA, NEW YORK.

HYDROAEROPLANE.

1,213,000.

Specification of Letters Patent.

Patented Jan. 16, 1917.

Application filed January 21, 1916. Serial No. 73,324.

To all whom it may concern:

Be it known that I, LOUIS PHILIP PEREW, a citizen of the United States, and a resident of North Tonawanda, in the county of Niagara and State of New York, have invented a new and Improved Hydroaeroplane, of which the following is a full, clear, and exact description.

While certain features of my invention 10 may be embodied in aeroplanes generally, the invention, in its entirety, is more particularly intended for embodiment in hydro-aeroplanes.

An object of my invention is to provide a 15 flying machine so constructed that a balancing and stabilizing thereof may be effected without the employment of stabilizing elements additional to the main planes; the stated object is effected by a transverse shifting of the planes and their frame structure, to displace the mass represented thereby, and variously dispose the same relatively to the 20 mass of the main body of the machine and variously position, relatively to the longitudinal center of the machine, the total surface presented by said planes and frame structure.

A further object of the invention is to control the ascent and descent of the machine 25 through the medium of elements displaceable in a fore and aft direction to vary the center of gravity as required, to thereby vary the angle of the planes with respect to the direction of travel and maintain the balance 30 under the resistance of the planes at a given angle; and said object is attained by a displaceable structure at the center of the machine, including a steering rudder, the mass of which is thus utilized in controlling ascent and descent, in addition to the usual 35 function of the rudder in controlling the lateral direction of the machine, the rudder in practice furthermore having a boat form to materially contribute to the total buoyancy and to balance or "trim" the machine 40 when in the water, as well as to constitute a means for steering the machine on land.

Further objects of the invention will be apparent from the particular description 45 following.

Reference is to be had to the accompanying drawings forming a part of this specification in which similar reference characters indicate corresponding parts in all 50 the views.

Figure 1 is a plan view of a flying machine

embodiment my invention; Fig. 2 is a front elevation, partly in section as indicated by the line 2—2, Fig. 1; Fig. 3 is a longitudinal vertical section on the line 3—3, Fig. 2; 60 Fig. 4 is a transverse section representing one of the boat structures forming part of the machine; Fig. 5 is a diagrammatic plan view showing the planes moved to the right of the central position; Fig. 6 is a similar 65 view showing the planes moved to the left of the central position; Fig. 7 is a plan view showing one position of the longitudinally displaceable structure including the rudder; Fig. 8 is a view similar to Fig. 7, showing 70 the said longitudinally displaceable structure in position forward of that indicated in Fig. 7.

In constructing a practical embodiment of my invention, having in view the use of the 75 flying machine as a hydro-aeroplane, I provide a body of the general character of a catamaran, comprising two parallel buoyant boat-like structures 10, hereinafter designated as boats. The boats 10 are rigidly 80 connected to suitable frame work, designated generally by the numeral 11, the said boats and frame work constituting the body of the machine.

Transversely of the body, are parallel 85 guide-ways 12, presenting at the upper sides thereof, grooves undercut at opposite sides. In said guides 12, slides 13 have guided movement, the slides being of inverted T-shape in cross section and being in rigid relation to the transversely disposed frame 14 carrying suitable planes. All of the planes, as here shown, are rigid, the rigidity of the planes being possible owing to the provision for stabilizing and balancing of the machine, 90 in accordance with my invention, without warping or otherwise manipulating the planes, and without the employment of a separate stabilizer. The planes include a top plane 15, a bottom plane 16, and an 95 intermediate plane which is formed in two side sections 17, there being an opening between the sections at the center of the machine to permit movements of an operator. The machine is propelled by any suitable 100 propeller 18, the shaft 19 of which is suitably journaled in the plane frame 14 and driven by any suitable motor (not shown), the motor, in practice, being mounted on a platform which may consist of planks 20, 110 forming elements in the frame 14 at the center of the bottom plane 16. I provide

means, as hereinafter described, for shifting the structure 14 and the planes carried thereby, transversely of the machine, either to the right or to the left, for balancing and 5 stabilizing the machine by displacing the mass represented by the planes and their frame, with respect to the relatively fixed mass, and by variously disposing, relatively to the longitudinal center of the machine, 10 the front surface presented by said frame and planes.

The rudder 21 in my improved machine has a boat form to contribute to the buoyancy of the machine when in the water. 15 Said rudder turns on a vertical pin 22, extending through a transverse member of a structure 23, which is slideable on the machine in a fore and aft direction to displace said structure 23 and rudder 21 and variously dispose the mass thereof relatively 20 to the mass represented by the remainder of the machine, whereby to balance the machine with the planes disposed at an angle for ascent or descent. The frame 23 moves in guides 24, forming part of the frame 11, 25 at the opposed sides of the boats 10, as best seen in Fig. 2. The means for shifting the structure 23 will be described presently.

To turn the rudder 21 on its pivot 22 for 30 steering the machine, a rope, chain, or like flexible element 25, connects at its ends with the rudder head, yoke, or the like, at 21^a, and extends over suitable guides 25^a on the frame 23 to the forward end of the latter, 35 where it is given one or more turns about a capstan or vertical drum 30. The drum 30 may be turned by a lever, steering wheel, or other suitable means; for the purpose of illustration a steering wheel 26 is shown on 40 a steering shaft 27, which is provided with a bevel pinion 28 that meshes with a similar pinion 29 on the shaft of the drum 30.

To shift the frame 23 forward and back, in the construction illustrated, a vertical 45 lever 31 is pivotally hung on the structure 14 or one of the planes carried thereby, and connected by a forwardly extending link 31^a (Fig. 1) with a reciprocating rack 32, said rack meshing with a pinion 33. In 50 fixed relation to the pinion 33 is a gear wheel 34, which meshes with a fixed longitudinally ranging rack 35 on the frame 11 at the front of the latter. Thus, by throwing the lever 31 forward or back, the gear wheel 34 will be caused to travel along the fixed rack 35 and carry the frame 23 and rudder 21 in 55 a fore and aft direction to variously position the same relatively to the remainder of the machine, as, for example, to the positions indicated diagrammatically in Figs. 7 and 8.

The illustrated means for shifting the structure 14 and the planes laterally to the right or to the left, in the illustrated example, includes a shifting lever 36, shown fully 60 in Figs. 2 and 3. It is to be understood that

the lever 31 is the same as the lever 36 so that an illustration of one discloses the form and arrangement of the other. The lever 36 is pivotally hung at its upper end on the frame 14 or one of the elements entering into 70 the plane 15, and carries at its lower end, a forwardly extending reciprocating rack 37, connected with the lever by a link 36^a. Said rack 37 meshes with a pinion 38 on a drum 39. A rope 40 is given one or more 75 turns about the drum 39 and extends rearwardly therefrom in two strands, through suitable guides 41 on the frame 23, from which guides the rope extends laterally as clearly indicated in Figs. 1, 5 and 6, to and 80 through suitable guides 42 on bars 43 of the frame 14 (see Figs. 1 and 2), from which guides 42, the rope ends 40 are returned on themselves and made fast as at 44, in any suitable manner on the structure 23. Thus, 85 by throwing the lever 36 forward or back, the drum 39 will be turned to cause the rope 40 to shift the planes to the right or to the left, as, for instance, from the position shown in Figs. 1 and 2, to a position such as 90 shown in Fig. 5, or that shown in Fig. 6. The levers, 31, 36, may have suitable handles 45 as indicated in Fig. 1, one of said handles being shown in full in Figs. 2 and 3. The shifting of the planes bodily to the right or 95 to the left, it will be obvious, will serve to balance the machine laterally and stabilize the same merely by displacing the mass of the planes and their frame structure relatively to the mass represented by the body 100 of the machine and the structure 23 and rudder 21, and at the same time variously disposing the front surface, presented by the said planes and their frame structure, 105 laterally of the machine.

The numeral 46 represents a transverse strip forming a forward guide for the ropes, 110 25, 40, which pass through a suitable arrangement of holes in said strip, there being 115 a guide strip 47 on the frame 23 near the rudder 21, through which the rope 25 passes.

The body boats 10 are provided with running wheels 48, and the rudder boat 21, with a similar running wheel 49. Each boat 115 is formed centrally with a well 50, the walls of the well serving to mount the respective wheels 48, 49. The said wells present vertical openings at the median line of the boats and each boat is formed at the keel with 120 a longitudinal groove 51 which communicates with the opening formed by the well of each boat. In the decks of the boats, suitable openings are formed, as indicated for example at 52, in Figs. 2 and 3. The arrangement is such that air will pass downwardly through the openings 52 and the wells 50 and along the keel grooves 51, and act to assist the boats leaving the water in 125 rising. As seen in Fig. 3, the rear wall 53 130

of the well 50 of the boat constituting the rudder 21, is inclined downwardly and rearwardly to direct the air to the groove 51 when the boat is underway in the water.

5 Having thus described my invention I claim as new, and desire to secure by Letters Patent:

1. A flying machine including separate spaced body sections rigidly connected, a 10 structure slideable in a fore and aft direction between said body sections, and a rudder carried by said slideable structure.

2. A machine of the class described including two buoyant boat-like body sections 15 spaced apart and disposed parallel with each other at opposite sides of the longitudinal center of the machine, a frame supported on said body sections and provided with a plane, means to shift said frame and plane transversely, a structure slideable in a fore and aft direction between said buoyant body sections, and a buoyant boat-like rudder carried by said slideable structure at the rear end of the latter.

25 3. A machine of the class described including a buoyant body, planes supported on the body, a structure slideable on the body in a fore and aft direction, and a boat-like rudder carried by said slideable structure.

30 4. A machine of the class described including a body, a frame transversely slideable on the body, said frame having a plane thereon and movable bodily therewith, a structure slideable in a fore and aft direction 35 on said body beneath the said slideable frame, a rudder carried by said structure, a flexible element connected with said rudder and extending therefrom forwardly to the front of said slideable structure, means

40 on the forward end of the slideable structure for actuating said flexible element, and means for laterally moving the transverse sliding frame and the plane, said last-mentioned means including a drum on the said

45 slideable structure, means for turning said drum, a flexible element wound on said drum

and extending rearwardly therefrom in the form of a double strand, guide means on the said slideable structure with which said last-mentioned flexible element has running 50 engagement, the said strands of said element extending laterally in opposite directions and having running engagement with the transversely sliding frame at opposite sides of the longitudinal center of the machine, 55 the strands being returned on themselves and made fast to the said slideable structure.

5. A machine of the class described including separated buoyant body sections, a plane supported on said body sections, a 60 buoyant body-like rudder in the rear of the said body sections, ground wheels on the buoyant body sections, and a steering ground wheel on the buoyant rudder.

6. A machine of the class described including a body, a frame transversely slideable on the body, said frame having a plane thereon and movable bodily therewith, and means for laterally moving the transverse sliding frame and the plane, said last-mentioned means including a drum on the said 65 slideable structure, means for turning said drum, a flexible element wound on said drum and extending rearwardly therefrom in the form of a double strand, guide means on 70 the said slideable structure with which said flexible element has running engagement, the said strands of said element extending laterally in opposite directions and having running engagement with the transversely 75 sliding frame at opposite sides of the longitudinal center of the machine, the strands being returned on themselves and made fast to the said slideable structure.

In testimony whereof I have signed my 85 name to this specification in the presence of two subscribing witnesses.

LOUIS PHILIP PEREW.
